UNITED STATES PATENT OFFICE.

ADELMER M. BATES, OF CHICAGO, ILLINOIS, ASSIGNOR, BY MESNE ASSIGNMENTS, TO BATES VALVE BAG CORPORATION, OF CHICAGO, ILLINOIS, A CORPORATION OF DELAWARE.

PIVOT-POINT ASSEMBLY.

Original application filed May 26, 1922, Serial No. 563,932. Divided and this application filed October 8, 1925. Serial No. 61,215.

My invention relates to a pivot point assembly, and has for its object to provide such an assembly which may be easily, cheaply and accurately made and assembled, and which will maintain the working parts in their proper relation to each other.

This application is a division of my prior application Serial No. 563,932, filed May 26, 1922, and issued November 17, 1925 as Patent No. 1,561,585.

My pivot point assembly may be used for a variety of purposes, but is particularly adapted for mounting a scale beam, and is shown and described as applied to that purpose.

In many cases, such as in machines for filling and weighing bags, the scale beam necessarily co-operates with other mechanism, so that it is advantageous to have its pivot point adjustable without danger of disturbing the proper relation of pivot assembly.

I have devised a pivot point assembly on which a scale beam may be adjusted angularly or laterally without danger of interfering with the proper action of the pivot. A structure by which this result may be obtained, as well as other features of my invention, will appear as the description proceeds.

In the accompanying drawings, forming a part of this specification, Figure 1 is a vertical section through a pivot point assembly embodying my invention; Fig. 2 is a section substantially on the line 2—2, Fig. 1; Fig. 3 is an end view of one of the members.

A support 1 is mounted in any suitable manner, and has therein a vertical bore 2. A pin 3 mounted in bore 2 has a head 4 formed with a knife-edge 5 on its upper side and an upright lug 6 at one end of the knife-edge. The knife-edge is substantially perpendicular to the axis of pin 3, and the surface of lug 6 next to the knife-edge is substantially perpendicular thereto. The lug is preferably an integral portion of head 4, so that there is no danger of disturbing the correct relation of the knife-edge and the adjoining surface of lug 6. Pin 3 and head 4 are made so that there is no danger of disturbing the relation of the knife-edge to the axis of the pin. This may be done either by making the parts integral or by accurately fitting the head upon the pin.

A scale beam 7 is provided with a transverse groove 8 in its under side; the groove being of proper size to receive a wearing block 9. The wearing block is laterally adjustable in groove 8, and may be fixed in adjusted position by a set screw 10. The under side of block 9 is notched to receive knife-edge 5, and the end 11 of the block is tapered to a point 12 at the end of the notch. End 11 may be cone-shaped, as shown, or may be shaped like a pyramid, or tapered to a point in any desired manner.

It will be readily apparent that the pivot point assembly holds the beam securely against displacement to the right, as shown in Fig. 1, because of the contact between point 12 and lug 6, and that this contact, as it occurs only at a point and that point is in line with the axis about which the beam turns, will result in the minimum of friction. Furthermore, pin 3 may be allowed to oscillate freely in hole 2, so that the scale beam may be swung laterally to co-operate as desired with other mechanism, without any danger of disturbing the relation of the notch in the wearing block to knife-edge 5, or that of bearing point 12 and lug 6. Likewise block 9 may be adjusted laterally of the beam without affecting the co-operation of block 9 and head 4.

The scale beam may be held by any suitable means against displacement to the left, as shown in Fig. 1; but I prefer to use pivot point assemblies, such as shown, in pairs, one having lug 6 at the right and the other having a similar lug at the left.

It will be seen from the above that I have devised a pivot point assembly wherein the co-operating parts of the pivot are so constructed and mounted that they satisfactorily achieve the object of my invention.

Various obvious changes may be made in the described embodiment of my invention without departing from the scope of the appended claims which define what I claim as new.

What I claim is:

1. In a balance point assembly, a member mounted to move about an axis and provided with a knife-edge substantially perpendicular to said axis and having an abutment at one end of said knife-edge, and a member

having a notch adapted to pivot on said knife-edge and having an end portion tapered to a point adapted to rest against said abutment.

5. 2. In a balance point assembly, a member mounted movably about a fixed vertical axis and having a substantially horizontal knife-edge on its upper surface and an abutment at one end of said edge, and a member having a notch in its lower surface adapted to pivot on said knife-edge, the end of said notched member towards said abutment being tapered to a point at the end of the notch.

3. In a balance point assembly, a stationary mounted member having a knife-edge formed thereon and having an integral lug extending at one end of said edge and having a bearing surface substantially perpendicular to said edge, and a member having a notch adapted to pivot on said knife-edge, the last said member tapering to a point at the end of the notch towards said lug.

4. In a balance point assembly, a support having a vertical bore therein, a pin fitting in said bore and having a head resting on the support, the head having, on its upper side,

a knife-edge and a lug at the end of the knife-edge, a beam having a transverse groove in its under side and a wearing block mounted adjustably in the groove, the wearing block having a notch in its lower side adapted to pivot on said knife-edge and the end of the block next to said lug tapering to a point at the end of the notch.

5. In a balance point assembly, a support having a vertical bore therein, a pin fitting in said bore and having a head at its upper end, the head having a knife-edge substantially perpendicular to the axis of the pin and an integral lug presenting a surface at one end of and perpendicular to the knife-edge, a beam having a transverse groove in its under side, and wearing block adjustable lengthwise in said groove, the block having a notch in its under side adapted to pivot on said knife-edge, and the end of the block next to said lug tapering to a point substantially in line with the axis of oscillation of the block on said knife-edge.

In testimony whereof I have hereunto signed my name to this specification.

ADELMER M. BATES.
